METALWORKING PROCESS AND
APPARATUS

Clarence W. Hazelett, Greenwich, Conn.

Application April 10, 1943, Serial No. 482,606

19 Claims. (Cl. 22—57.2)

1

This invention relates to a metal working process for the production of seamless tubing directly from molten metal. The invention relates further to one form of apparatus that may be used for the carrying out of the process. My invention relates further to modifications, both in the process and in the apparatus, for the production of round bars and bi-metallic seamless tubing.

At the present time, seamless tubing is manufactured commercially by several processes, all of which are relatively expensive for a number of reasons well understood by those skilled in the art. Seamless bi-metallic tubing is extremely expensive despite the many efforts that have been made to reduce the cost of manufacturing such tubing.

As I have already indicated, the object of my invention is the forming of seamless tubing directly from the molten metal, an object that those skilled in the art will undoubtedly appreciate has been frequently attempted but without success. The process and apparatus to be described hereinafter have actually been used by me for the manufacture of seamless tubing and have been found extremely successful. In describing my process and apparatus I shall of course outline certain theories of operation that I now believe to be true from those studies I have made of my process and apparatus. However, I do not wish the patent claims to be granted me to be limited by the theories I shall set forth since those theories may prove not to be entirely correct or complete. It will be well also to consider that the apparatus that I shall outline hereinafter is merely exemplary of one form of means whereby my process may be successfully carried on, and that other arrangements of apparatus may be successfully used following my teachings to the art. It will be well to remember also, that while I shall describe a process in which several steps are used, sub-combinations of the process, omitting certain steps, may yield excellent results, and I shall include in this application claims covering such sub-combinations.

As an important feature of my invention whereby I obtain seamless tubing directly from molten metal, the metal is poured on to a rotating mold in such a manner as to be carried away by the mold, the metal solidifying on the mold as it is being carried away. It is a further preferred feature of my invention that the metal poured onto the mold rotates with the mold by means that may be provided for the particular purpose.

As a still further feature of my invention, the metal deposited on the mold is moved endwise

2

relatively to the pouring plane of the metal. Preferably this endwise movement takes place at the same time that the metal is rotating with the mold, and preferably effects movement of the metal relatively to the rotating mold. It is obvious that the endwise and rotary movement of the metal will result in the solidifying metal being in the form of a helix.

It is a further feature of my invention that the convolutions of the helix, or the helical ribbon of metal that is deposited on the mold, are welded to one another. It is a particular feature of this portion of my invention that this welding takes place through the overlapping of the successive convolutions of the helical ribbon of metal, and with the last poured metal welding to the immediately preceding convolution deposited on the rotating mold because both the last poured metal and the preceding convolution are in a condition to permit welding. Under another theory of my invention, the several convolutions may be juxtaposed and be welded through a rolling of the convolutions into welded relation. In the preferred form of my invention, however, the several convolutions are overlapped and are rolled into welded relation.

In this preferred form of my invention, this rolling action takes place just after the metal is poured onto the rotating mold, but those skilled in the art will appreciate that the rolling may take place at various points depending on the cooling conditions, the metal, and other variable factors. Those skilled in the art will readily appreciate also, after a full study of the specification and drawings of this application, that my invention need not necessarily be carried on in the exact manner which I now consider the preferred form, and that variations thereof within the scope of my teachings to the prior art will readily occur to those skilled in the art.

As a further feature of my invention, I prefer to roll the metal tubing additionally, at a point beyond its initial formation through welding of the convolutions thereof, and this additional rolling is useful in disposing of the surplus metal that may be deposited on the inner surface of the tubing, and in the smoothing thereof.

As a further feature of my invention I am able to form a bi-metallic tubing through the utilization of the first formed tubing as the mold for a second formed inner tubing. Somewhat similarly, my invention is applicable to the forming of a solid bar of metal through the pouring of metal into the seamless tubing that is formed

by the utilization of the apparatus and process of my invention.

I have thus described generally the main features of my invention and my contribution to the prior art in order that the breadth of my invention and its relation to the prior art may better be appreciated. The general description presented will also help in an appreciation of the particular steps of the process to be outlined hereinafter, and to the understanding of a preferred form of the apparatus that I shall hereinafter disclose for carrying on my process. Naturally, as I have already suggested, the nature of my invention is such that it should not be limited by the particular apparatus I shall describe, the particular sequence of the steps that I shall set forth, nor the theory of operation of the process, since variations of the process steps, the theory of operation, and the apparatus itself will readily occur to those to whom the disclosure of my invention is presented.

Referring now to the drawings, Fig. 1 is a vertical diagrammatic section of a machine used by me for carrying out the process of my invention. Fig. 2 is a section of a modified form of the machine of Fig. 1 used for forming solid round bars. Fig. 3 is an end view of the machine shown in Fig. 1. Fig. 4 is a modified form of the invention of Figs. 1 and 2 illustrating the manner in which my invention may be utilized to form a bi-metallic bar. Fig. 5 is a section through a portion of a tube formed by my invention and illustrating in exaggerated form the manner in which the convolutions of the helical ribbon of metal are used to form a finished tube.

Referring now more particularly to the drawings, the rotating mold of my invention is designated by reference numeral 10, and is formed with an inner surface 11 that may be tapered outwardly as is clearly evident from Fig. 1. That portion of the inner surface designated by reference numeral 11a, is used to determine the outside diameter of the tubing to be formed, the tapering of the surface 11 being adapted, as will herein-after appear more clearly, to allow for a ready withdrawal of the finished tubing from the mold 10. The mold 10 is adapted to be driven by what I term a driving roll 13 secured to a shaft 14 and driven by a gear 15 through a pinion 16. The pinion 16 may be on the shaft of a variable speed motor and is used to drive the roll 13 and thereby impart rotation to the mold 10 as will readily be apparent. The shaft 14 is well supported by ball bearings 17 through a substantial standard 18 and is thus held in suitable operating relation to the mold 10.

Cooperating with the driving roll 13 are a pair of backing rolls 20 shown in Fig. 3, and probably best illustrated in Fig. 1. Each roll 20 is supported by a bearing 21 relatively to an eccentric sleeve 22 mounted on a shaft 23, and each of the shafts 23 is held in fixed relation by a stud 24 relatively to a standard 25. Each of the eccentric sleeves 22 is formed with an arm 26 whereby it may be rotated relatively to the shaft 23 to move the roller 20 mounted thereon toward and away from the mold 10. In this way, an adjustment of the rollers 20 is readily obtained. The eccentric sleeves 22 may be secured in any adjusted position by thumb turns 27 threaded onto adjusting studs 28 that traverse slots in the arms 26 and flanges 29 of the standards 25.

The rotating mold member 10 is formed with a shoulder 30 at its left end in Fig. 1, and between this shoulder and the rollers 13 and 20 there may

be placed a thrust washer 31. A second thrust washer 32 is applied between the rollers 13 and 20 and a drive ring 33 that is in threaded assembled relation to the mold member 10. The threaded drive ring 33 is equipped with a series of resilient drive fingers 34 that are adapted to engage and rotate what I term "bait," and thereafter the tubing that is formed in the mold member 10, all as will be hereinafter set forth in more detail.

For cooling the tubing, I illustrate cooling pipes 35 in Fig. 1, these being merely diagrammatically shown. Naturally, other cooling sources may be provided and may be located as may be required, depending upon the quality of tubing manufactured, the material utilized and other variable and controlling factors.

The metal that is poured onto the surface 11 of mold member 10 for the forming of tubing, is supplied from a ladle 40 and through its pouring spout 41 into an adjustable metal pourer 42. The pourer 42 is readily adjustable through means designated generally by numeral 43, so that the quantity of metal M flowing onto the mold surface 11, and that part of the surface 11 on which it is deposited may be determined, all as illustrated in Fig. 1.

For rolling the surface of the tubing that is formed in the mold 10 by the metal M, I use a roller 45 mounted on a standard 46 through the intermediary of ball bearings 47. The roller 45 is hollow and houses therein a pipe 48 through which a coolant may be fed to the roller 45. In the particular relationship of the parts illustrated, the roller 45 is adapted to contact the metal M poured onto the mold 10 just after that metal is actually deposited on the mold 10, it being understood that preferably the speed of rotation of the mold 10 is such that the metal will adhere to it by centrifugal force and be moved toward roller 45. It will of course be appreciated that under certain conditions the metal will adhere to mold 10 sufficiently merely through cooling, whereby to be carried by that mold into coaction with the roller 45.

As was set forth generally in the earlier part of the specification, it is a preferred feature of my invention that the solidifying metal deposited on the mold 10 be moved endwise relatively to the mold 10 and the point where the metal is deposited onto the surface 11. It is preferred also that this endwise movement take place as the metal is rotated with the mold 10.

For rotating the metal with the mold 10, the resilient drive fingers 34 are utilized, those fingers, it being remembered, being secured to the driving ring 33. For moving the tubing endwise, I utilize a friction screw member 50 mounted on the right hand end 23a of the same shaft 23 on which is mounted the backing roll 20 illustrated in Fig. 1. The pressure of the friction screw roller 50 against the tubing may be regulated by an eccentric sleeve 51 that functions in exactly the same manner as do the eccentric sleeves 22 already described in considerable detail. Mounted about the shaft 14 through a bushing sleeve 52 is a further backing roll 53, the function of which will be quite apparent to those skilled in the art.

For starting the endwise and rotary movement of the poured metal I utilize what I term bait. This bait is in the form of a sleeve 54 that is formed at its extreme left end with a very thin section 55 pierced for a series of holes 56 into which the metal M will enter. The holes 56

serve to bond the metal firmly to the bait as is apparent. The bait 54 will of course be moved endwise in the direction of the arrow 57 by the screw friction roller 50 or by other means, while rotated by the resilient drive fingers 34, and will carry with it the solidifying metal tube. It is obvious that the rotary and endwise movement imparted to the metal deposited on the mold M will cause the metal to assume the form of a helical ribbon of metal. Naturally, the several convolutions of this helical ribbon of metal may be made to overlap somewhat by an adjustment of the pouring rate relatively to the speed of rotation of the mold 10 and the endwise movement of the solidifying metal. The roller 45 will roll the convolutions to form a consolidated tubing with the convolutions preferably disappearing into one another and welding to one another. This welding will take place because the last poured metal coming in contact with the roller 45, as well as at least the immediately preceding convolution of the helical metal ribbon, are in a state to permit welding of the two. My process has actually been carried on successfully to make tubing of six inches outside diameter and with a wall thickness ranging from .125 to .5 inch. In making this tubing I have rotated the mold 10 at a speed of 130 R. P. M. and have moved the solidifying metal endwise at the rate 6-18 inches per minute.

Under some conditions, the several convolutions of the helical metal ribbon may be poured so as to lie merely juxtaposed. In such an event, the roller 45 will be relied upon to roll the convolutions of the helical metal ribbon into welded relation to form a consolidated metal tube.

The several welded convolutions formed by roller 45 will of course present a smooth exterior surface as is required. The inner surface formed by the metal forced upwardly by surface 45a of roller 45 will be relatively rough. It is generally necessary to provide a supplemental roller for acting on the inner surface, although in many cases a surface such as is normally formed will be quite adequate. A supplemental roller for rolling a smooth inner surface when desired is designated by reference numeral 60 in Fig. 1 and is equipped with a pipe 61 carrying coolant thereto. This roller 60 may be located at any desired point in the tubing and may assume any shape found suitable.

In Fig. 3 the manner in which the rollers 45 and 60 are mounted is rather clearly set forth. There it will be noted that the bracket 46 on which the roller 45 is mounted, is pivoted at 62 on a main support 63. The main support 63 has an arm 64 on which is mounted a guide rod 65, and the bracket 46 is formed with a disc-like portion 66 pierced at 67 for passage of the guide rod 65. A spring 68 bears against portion 66 of the bracket 46, this spring being mounted about the guide rod 65 and adapted to have its pressure adjusted by a nut 69 in threaded engagement with a threaded end of rod 65. It is obvious that through the adjustment of the pressure of spring 68, the pressure of the roller 45 against the poured metal may be determined. Through a somewhat similar but independent arrangement, the pressure of a spring 68a against a bracket 46a on which the roller 60 is supported, may also be adjusted. Thus, the pressure of the roller 60 may be independently determined. It will be obvious to those skilled in the art that my showing of this structure is purely diagrammatic and that many other mechanical struc-

tures for driving the mold 10 and rolls 45 and 60, as well as moving the bait and tubing, will readily occur to those skilled in the art.

In Fig. 2, I illustrate a modification using certain parts of Fig. 1 in a manner to yield a solid round bar. In Fig. 2 the mold is designated by reference numeral 10a and is adapted to receive metal through a pouring spout 42a adapted for adjustment similarly to spout 42 of Fig. 1. The mold 10a is shown vertically positioned in Fig. 2 but may assume an angular or more nearly horizontal position. A roller 45c cooperates with the metal moving from the pouring spout 42a in substantially the same manner as in Fig. 1. Because a solid bar is to be formed, the beveled portion 45d of roller 45c may be relatively large and in the form shown it rolls a considerable portion of the metal bar and contributes the smooth outer surface required. Sufficient additional metal is poured to consolidate with the rolled metal to form the section B of a solid bar of metal. The bait in Fig. 2 is designated by reference numeral 54a and is similar in its action to bait 54 of Fig. 1 except that it may have a solid end where the pouring is vertical or substantially so. Coolant is supplied by a device 71 all in a manner which will be understood now by those skilled in the art.

In common with the modification of Fig. 1 the mold 10a may be tapered so as to make it possible to more readily separate the cylindrical product from the mold as the said product is rotated with the mold and is moved endwise relatively to the mold. It is rather obvious that the invention of this modification yields a solid cylindrical bar of metal having preferably a rolled outer surface contributed by the action of the surface 45d of roller 45c, and that even a larger part of said bar may be rolled by making the roller 45c of relatively larger diameter.

In Fig. 4 I illustrate a vertical section of a further modification of my invention in which the mold is indicated by reference numeral 10b, a primary metal spout by reference numeral 42b and a primary roller by reference numeral 45b. Coolant is supplied by a device 35a whose action is apparent. The parts 10b, 42b and 45b cooperate as do the parts 10, 42 and 45 of the modification of Fig. 1. This cooperation yields a tube T' that is moved endwise as it is rotated relatively to the mold 10b just as in the earlier modification. The tube T' as formed by the roller 45b, serves as the outer portion of a bi-metallic bar, the core of which is formed by the pouring of additional metal into the tube T' by a second spout 70c. The roller 45b is adapted to roll a part of the additional metal issuing from the pouring spout 70c so that the said metal is welded to the outer tube T' along the general line W shown in Fig. 4. Where the metal issuing from the spout 70c of this modification of my invention is a metal different from the metal issuing from the spout 42b, a bi-metallic bar is formed.

By referring back now to Fig. 1, I shall describe a still further modification of my invention whereby I make bi-metallic tubing through employing the basic process and apparatus of my invention. In Fig. 1 I show in phantom lines an additional spout 75 adapted to flow a metal dissimilar from that furnished through spout 42. This dissimilar metal flows on the interior surface of the exterior tube formed on mold 10 by roller 45 at a point when the metal of the exterior tube is in a condition to have welded thereto the additional and dissimilar metal from spout 75. The additional metal will form an internal

tube through the pressure of a roller 45f similar to the roller 45 used in forming the outer tube and this inner tube will of course be welded to the outer tube. For the sake of clarity in the drawings, both spout 75 and roller 45f are shown displaced to the right more than would actually be the case under operating conditions.

In Fig. 5 I illustrate in exaggerated form one example of the manner in which the several convolutions of a helical ribbon of metal are used by my process to form a consolidated metal tube. Fig. 5 illustrates well the action of roller 45 and its surface 45a in rolling the metal, the angular lines formed at 77 by the shading representing the welded junctions of the helical ribbon convolutions in a typical tube. The normal irregular inner surface that is formed is well shown also.

I believe that the basis of my invention and the several different conditions under which it may be employed, will now be clearly understood by those skilled in the art.

I therefore now claim:

1. A process for forming tubing directly from molten metal that comprises pouring a ribbon of metal directly on a rotating mold member, effecting the solidifying of said metal on said mold member as said mold member rotates, drawing said metal endwise relatively to said mold member while said metal rotates with said mold member, whereby the said metal is in the form of a helical metal ribbon, determining the rotation and endwise movement of the metal at such a rate relatively to the rate of pouring of the metal that the successive convolutions of the helical ribbon of metal deposited on said mold member are at least juxtaposed, and the last convolution is in such a state that the metal last poured on said mold member may be welded to said last convolution, and applying the pressure of a rolling surface radially of said mold member to weld said metal to the last convolution while also applying the pressure of a tapered rolling surface axially of said mold member against the surplus metal flowing lengthwise and from under said first rolling surface onto the last convolution.

2. A process for forming tubing directly from molten metal that comprises pouring a ribbon of metal on a rotating mold member, effecting the solidifying of said metal on said mold member as said mold member rotates, drawing said metal endwise relatively to said mold member while said metal rotates with said mold member whereby the said metal is in the form of a helical metal ribbon, and determining the rotation and endwise movement of the metal at such a rate relatively to the rate of pouring of the metal that the successive convolutions of the helical ribbon of metal deposited on said mold member overlap, and the last poured metal convolution is applied to said mold member while at least the immediately juxtaposed convolution is in such a state that the last poured metal convolution will weld to the said immediately juxtaposed convolution, and applying rolling pressure to said poured ribbon of metal after it is deposited on said mold member and while it is still molten, and with the final rolling pressure so applied being both radial and axial relatively to said mold whereby the said pressure consolidates and welds to one another the successive convolutions of the helical metal ribbon to form a tube.

3. Those steps in the process of forming tubing directly from molten metal that comprise pouring metal on the inner surface of a rotating mold,

applying rolling pressure to said metal radially of said mold just after it is deposited on said surface whereby to consolidate and solidify said metal while permitting the metal to flow axially of said mold away from the zone of radial pressure application, applying axial pressure to said flowing metal as it leaves the zone of radial pressure application whereby to weld said metal to the previously deposited metal, and rotating said metal at the speed of rotation of said mold and moving it endwise relatively to said mold.

4. A process for forming tubing directly from molten metal that comprises pouring molten metal on a revolving mold surface, withdrawing the metal deposited on said mold surface in a direction substantially parallel to the axis of rotation of said revolving mold surface while said solidifying metal rotates with said mold surface, applying rolling pressure to said solidifying metal whereby to form a consolidated tube, and later flowing additional metal on the inside surface of the said tube while the metal of said tube is in said mold and in a state to permit welding thereto of the additioning metal.

5. A process for forming tubing directly from molten metal that comprises pouring molten metal on a revolving mold surface, subjecting the metal coming in contact with said mold surface and before it has entirely solidified, to pressure by a rolling surface directed toward said mold surface, withdrawing the solidifying metal deposited on said mold surface in a direction substantially parallel to the axis of rotation of said revolving mold surface while said solidifying metal rotates with said mold surface, adjusting the speed of rotation of said revolving mold relatively to the pouring rate of said metal and the extent of said withdrawal movement so that the metal ribbons deposited on said mold surface during successive revolutions will be welded to one another by the rolling action of said rolling surface, and flowing additional metal on the inside surface of the resulting rotating tube of metal while said tube is in a state to permit welding thereto of said additional metal, and rolling said additional metal against the said inside surface to weld said additional metal thereto.

6. A process for forming tubing directly from molten metal that comprises pouring a thin film of molten metal on the surface of a revolving mold, subjecting said film of metal while solidifying to pressure by means of a surface roll to form a tube, and pouring additional molten metal on the resulting metal tube and subjecting the additional metal to rolling pressure quickly enough so that the additional metal is welded to the first formed tube.

7. A process for forming solid cylindrical bars directly from molten metal that comprises pouring molten metal on a revolving mold surface to form a tube, rotating and moving the said tube endwise of said mold surface, and flowing additional metal into the rotating tube to fill said tube while said tube is in a state to permit welding thereto of said additional metal to form therewith a solid cylindrical bar.

8. In a machine of the class described, a rotating mold, means for pouring metal on the surface of said mold, means for rotating said mold and the metal solidifying on said surface, means for moving said solidifying metal endwise of said mold as it rotates with said mold whereby said solidifying metal is formed on said mold as a helical metal ribbon a roller having a cylindrical pressure surface positioned for co-action with

said mold in that zone where the poured metal is plastic for applying pressure to said solidifying metal directed radially towards the surface of said mold, and said roller having its end surface tapered inwardly in the direction of movement of said helical metal ribbon whereby to apply a pressure component to said metal ribbon axially of said mold in the direction of movement of the metal ribbon to that metal that flows from under the said cylindrical surface.

9. In a machine of the class described, a rotating annular mold, means for pouring metal on the surface of said mold, means for rotating said mold and the metal solidifying on said surface, means for moving said solidifying metal endwise of said mold as it rotates with said mold whereby said solidifying metal is formed on said mold as a helical metal ribbon, and a roller having an end surface tapered inwardly away from said mold for applying rolling pressure radially and angularly to the successive convolutions of said helical metal ribbon just after the metal is deposited on said mold whereby to weld the successive convolutions to one another.

10. In a machine of the class described, a rotating ring-like mold member, means for pouring metal on the inner surface of said rotating mold member as it rotates whereby the metal deposited on said mold member will be rotated with said mold member as it solidifies on said mold member, means for moving the metal endwise as it rotates with said mold member whereby said metal will assume the form of a helical ribbon of metal, rolling means having surfaces shaped for applying final rolling pressure both axially and radially to the convolutions of said helical ribbon just after the metal is poured on said inner surface, and means mounting said rolling means opposite that portion of the inner surface of the rotating mold where the metal is not solidified and is adapted for solidification and welding to the previously deposited metal under the influence of said rolling surfaces.

11. In a machine of the class described, a rotating annular mold, means for pouring metal on the inner surface of said mold, means for rotating said mold and the metal solidifying on said surface, means for moving said solidifying metal endwise of said mold as it rotates with said mold whereby said solidifying metal is formed on said mold as a helical metal ribbon, means for pouring an inner ribbon of metal on the inside surface of said first ribbon of metal, and means for applying rolling pressure to said inner ribbon to weld its convolutions to one another and to said first ribbon of metal.

12. In a machine of the class described, a rotating annular mold, means for pouring metal on the inner surface of said mold, means for rotating said mold and the metal solidifying on said surface, means for moving said solidifying metal endwise of said mold as it rotates with said mold whereby said solidifying metal is formed on said mold as a helical metal ribbon, means for applying pressure to the convolutions of said helical metal ribbon whereby to weld said convolutions to one another to form a metal tube, means for pouring in like manner an inner ribbon of metal on the inside surface of said tube, and means for applying rolling pressure to said inner ribbon of metal, to weld its convolutions to one another and to said tube.

13. In a machine of the class described, a rotating mold, means for pouring metal on the surface of said mold, means for rotating said mold

5 and the metal solidifying on said surface, means for moving said solidifying metal endwise of said mold as it rotates with said mold, a roller having a pressure surface for applying radial pressure to said solidifying metal directed towards the surface of said mold, yielding means pressing said roller toward the said surface of the rotating mold, said pressure surface terminating in a tapered end surface for transmitting rolling pressure to said metal axially of said mold in the direction of movement of the solidifying metal, and means mounting said roller within said mold with its rolling surfaces positioned where said metal is in a plastic condition on the surface of said mold.

15 14. In a machine of the class described, a rotating annular mold, means for pouring metal on the surface of said mold, means for rotating said mold and the metal solidifying on said surface, means for moving said solidifying metal endwise of said mold as it rotates with said mold whereby said solidifying metal is formed on said mold as a helical metal ribbon, a roller for rolling said solidifying metal and terminating in an end pressure surface tapered inwardly axially thereof in the direction of movement of said solidifying metal, and means mounting said roller for rotation with its end surface in that zone of the mold where the metal poured on the mold surface remains plastic whereby said roller applies a pressure component against said solidifying metal directed radially toward the surface of the mold and a pressure component in the direction of movement of said solidifying metal, and with 20 said end surface rolling the metal flowing endwise from under the pressure roller.

25 15. A process for forming tubing directly from molten metal, that comprises pouring a ribbon of metal on the surface of a rotating mold member, subjecting the metal coming in contact with said surface and while it is plastic, to pressure first by a rolling surface directed radially toward said mold member and finally to pressure by a second rolling surface directed at least partially axially of said mold member, and with said radially directed rolling surface forcing the metal against the mold surface while the surplus metal flowing axially from under the end of said radially directed rolling surface is finally pressed by said 30 second rolling surface axially against metal that has just moved from under said radially directed rolling surface.

35 16. A process for forming tubing directly from molten metal, that comprises pouring a ribbon of metal on the surface of a rotating mold member, subjecting the metal coming in contact with said surface and while it is plastic, to yielding pressure by a first rolling surface directed radially toward said mold member and finally by a second rolling 40 surface directed both axially and radially toward said mold member, and with said radially directed rolling surface forcing the metal against the mold surface while the surplus metal flowing axially from under said radially directed rolling 45 surface is pressed by said second rolling surface axially against metal that has just moved from under said radially directed rolling surface.

50 17. In a machine of the class described, a rotating annular mold, means for pouring metal on the inner surface of said rotating mold as said mold rotates whereby the metal deposited on said mold will be rotated with said mold as it solidifies on said mold, a roller having a surface substantially parallel to the inner surface of the mold, 55 means mounting said roller for applying rolling

11

pressure to said metal directed against the surface of said mold just after said metal is deposited onto said inner surface, said roller terminating in a tapered surface just beyond the point where said metal is deposited onto said mold whereby to allow the flow of surplus plastic metal angularly inwardly of said mold and under said tapered roller surface, said tapered roller surface pressing the surplus plastic metal angularly while rolling it axially against the metal previously deposited on said mold, and means for moving the metal endwise of said mold as said metal rotates with said mold.

18. In a machine of the class described, a rotating annular mold, means for pouring metal on the inner surface of said rotating mold as said mold rotates whereby the metal deposited on said mold will be rotated with said mold as it solidifies on said mold, a roller having a surface substantially parallel to the inner surface of the mold, means mounting said roller for applying rolling pressure to said metal directed against the surface of said mold just after said metal is deposited onto said inner surface, means yieldingly pressing said roller on its mounting means radially of said mold, said roller terminating in a tapered surface just beyond the point where said metal is deposited onto said mold whereby to allow the flow of surplus plastic metal angularly inwardly

12

of said mold and under said tapered roller surface, said tapered roller surface pressing the surplus plastic metal angularly while rolling it axially against the metal previously deposited on said mold, and means for moving the metal endwise of said mold as said metal rotates with said mold.

19. In a machine of the class described, a rotating annular mold, means for pouring metal on the inner surface of said rotating mold as said mold rotates whereby the metal deposited on said mold will be rotated with said mold as it solidifies on said mold, roller surfaces for applying rolling pressure to said metal, one of said surfaces being substantially parallel to the inner surface of the mold whereby its pressure is directed radially toward the surface of said mold, said roller surface being positioned in said mold to contact said metal just after said metal is deposited onto said inner surface, the other of said roller surfaces tapering inwardly radially of said mold and positioned inwardly beyond said first roller surface, whereby said tapered surface presses the surplus metal flowing from under said first roller surface angularly and axially while rolling it against the metal previously deposited on said mold, and means for moving the metal endwise of said mold as said metal rotates with said mold.

CLARENCE W. HAZELETT.
